JOSEPH POWER DAWSON, OF CHARLESTON, WEST VIRGINIA.

METHOD OF MINING COAL.

Application filed March 26, 1924. Serial No. 702,106.

To all whom it may concern:

Be it known that I, JOSEPH POWER DAWSON, residing at Charleston, in the county of Kanawha and State of West Virginia, and a citizen of the United States, have invented certain new and useful Improvements in Methods of Mining Coal, of which the following is a specification, reference being had to the accompanying drawing, 10 forming a part thereof.

This invention relates to a method of mining coal, particularly bituminous coal, and has for its object to provide a method by which a body of coal lying in approximately horizontal position between a lower stratum, sometimes termed the pavement, of slate or other rock formation, and an overhanging or roof stratum of slate or the like, may be rapidly and safely mined with 15 safety to the miners and at the least possible expense.

In the mining of such bodies of coal, which are often many feet in width and length, it is usual to first cut parallel entries 20 or passageways at suitable distances apart, thus dividing the body of coal into masses or blocks with two parallel sides. In the long wall system of mining, the block of coal between the two parallel entries is 25 mined in slabs which are the masses of coal removed by a continuous cut of the cutting machine and the subsequent knocking or shooting down. The mining operation is usually conducted along only one 30 side of the block of coal at one time. Where successive slabs of coal of equal length are 35 mined, difficulty is found in avoiding the falling of the roof or overhanging wall without leaving at intervals pillars of coal or introducing other supports, usually timbers, which interfere with the regular operation 40 of the mining machines. Extensive timbering of the mine is expensive and the leaving of large and numerous pillars is 45 uneconomical, and both add to the difficulty of getting the coal out of the mine.

It is the purpose of my invention to provide a method by which the coal may be broken down in slabs in such manner that 50 the operation may be conducted without risk of premature falling of the roof and with little need for timbering or leaving supporting pillars.

With the objects above indicated and 55 other objects hereinafter explained in view,

my invention consists in the method herein-after described and claimed.

Referring to the drawing:

Figure 1 is a plan view of a body of coal blocked off by parallel entries; 60

Figure 2 is an elevation view of the body of coal from the entry 2 showing the area B of Figure 1 removed;

Figure 3 is an elevation view of the body of coal from the entry 1 showing the area C of Figure 1 removed; 65

Figure 4 is a cross sectional view on line 4—4 of Figure 1; and

Figure 5 is a cross sectional view on line 5—5 of Figure 1. 70

In the drawings, 1 and 2 indicate parallel entries driven into the body of coal at such distance apart as to leave between them a mass or block of coal having parallel side walls. 3 indicates a relatively long slab 75 mined by a mining machine, or otherwise, along and parallel with entry 1 and of such width as may be readily under-cut or otherwise cut by a mining machine so as to be subsequently knocked down, loaded on cars 80 and removed. 4 indicates a second slab parallel with the slab 3 but of less length and 5 indicates a third slab also parallel with slabs 3 and 4 but of less length than slab 4. 6, 7, 8 indicate successive slabs each 85 parallel with the entry 1 and each of less length than the preceding slab. As this slabbing process goes forward, timbers are usually used for holding the roof up. This slabbing is continued until the entry 2 is 90 reached, unless, before it is reached, it is found that the area of roof from beneath which the coal has been removed becomes too great to be supported without excessive timbering. The extent to which the slabbing operation begun from entry 1 can be 95 carried will depend upon the character of roof, the tendency to fall, and the consequent need of timbering varying greatly in different mines and in different parts of 100 the same mine. In the construction shown in the drawing, it is assumed that the slabbing operation begun from entry 1 is continuous until entry 2 is reached and the space indicated by A is cleared of coal. 105

The face 12 left by the operation described is at an oblique angle to the line of the entries 1 and 2. The portion A of the block of coal which has been mined by the operation described is triangular and the roof 110

over the portion of the block removed needs little or no support near entry 2 but may need timber support near entry 1. When the slabbing operations described have reached entry 2, the mining is continued by undercutting and breaking down a relatively long slab 13 parallel with entry 2. A second slab 14 is then cut parallel with slab 13 but of less length, and successive slabs each of less length than the preceding slab are cut until entry 1 is reached, or until it is found necessary on account of risk of premature falling of the roof without excessive timbering to stop slabbing from that side. When the slabbing operation begun from entry 2 is stopped, a space indicated by B will be cleared of coal. The face 16 of the block of coal will be oblique to the entries but its obliquity will be opposite to that of the face 12 left by the slabbing operation begun from entry 1.

In resuming the mining, slabbing is begun from entry 1, a relatively long slab 17 being cut away along this entry. A second slab 18 parallel with 17 but of less length is then cut away and so on until the entry 2 is reached or the slabbing is stopped because of weakness of the roof, the face 19 left being oblique to the entries and its obliquity being opposite to that of face 16 and in the same general direction with face 12. By this operation, a triangular space C is cleared of coal.

35 The operation of slabbing first from one side of the block of coal and then from the other, cutting in each case successive slabs of diminishing length is continued until the end of the body of coal is reached, the face left in each case being oblique and the spaces A, B, C, D, and E cleared of coal by each operation being substantially triangular with the base of the triangle along the entry at which the slabbing operation was begun.

In each of the slabbing operations, the longest slab is cut parallel with the next to the entry and the roof above this slab is so near the support afforded by the coal, or other roof support, on the opposite side of the entry that there is little danger of its falling, and, while the successive slabs are at increasing distances from the entry, they are successively shorter and the length of roof left without support is successively decreased.

The method of mining as thus far described shows the invention in its simplest form in order to bring out the idea of the mining of the coal by the progressive removal of the roughly triangular areas A, B, C, D, and E. But in almost all mines, it will be necessary to vary the method of mining to suit the particular conditions in each mine depending on the hardness of the

coal, the weight of the roof, and the like. In a mine with average roof conditions, it will be necessary to timber along the irregular oblique faces, particularly in the middle portion as at 12, in order to hold the roof up.

It should be particularly noted that timbers may be used for either of two purposes, either for holding the roof up or forcing it to break at a desired point rather than flush against the coal. As the space between two oblique faces becomes smaller as the slabbing proceeds, the ease and practicability of holding the roof up increases.

Very important features of this method of coal mining are shown at 20 and 22. The cross sectioned space 20 indicates a pillar of any desired size or shape left in the coal body as a support for the roof. It should be noted that supporting pillars as at 20 can be left wherever necessary without seriously interfering with the slabbing and removing of the coal. The cross sectioned space 22 indicates a continuous wall or pillar left between the coal bodies D and E removed by the slabbing operation. The possibility of leaving these walls as at 22 to form a zig-zag supporting medium for the mine roof is one of the most desirable features of the mining system. Thus, it may be seen that suitable roof supports can be left wherever necessary with a minimum amount of timbering and little interference with the mining operations.

As shown at 21, the slabbing process as carried on in the space D may be continued on along an oblique face as well as simply in lines parallel with the entries. Working along the oblique face as well as along the parallel face serves to increase the length of face which can be cut in one cut of the mining machine. Additional slabs of coal may be taken anywhere that roof and bottom conditions permit.

With a roof of normal strength, there is much less danger of its falling where the slabbing is carried out as above described and much less timbering is needed than when the slabs cut are all of the same length.

It should be noted that this system of mining is not dependent on undercutting, but where cutting or undercutting is mentioned, it should be taken to refer as well to middle cutting or top cutting or any other way of cutting a slot or kerf in the coal.

Having thus described my invention, what I claim is:

1. The method of mining a body of coal lying between parallel entries which consists in breaking down and removing a relatively long slab along one entry, breaking down and removing successive parallel slabs each of less length than the preceding

slab so as to leave the face of the body of coal at an oblique angle to the direction of the entry.

2. The method of mining a body of coal lying between parallel entries which consists in breaking down and removing a relatively long slab along one entry, breaking down and removing successive parallel slabs each of less length than the preceding slab so as to leave the face of the body of coal at an oblique angle to the direction of the entry, then breaking down and removing a slab along the other entry to a point beyond the line of the end of the slab first broken down along the first entry, breaking down and removing successive slabs each of less length than the preceding slab so that the face of the body of coal left at the conclusion of the second slabbing operation will be oblique to the line of the direction of the entries and will be at an angle opposite to the angle of the face left by the first slabbing operation. 35
- 10 3. The method of mining a body of coal lying between parallel entries which consists in breaking down and removing a relatively long slab along one entry, breaking down and removing successive parallel slabs each of less length than the preceding slab so as to leave the face of the body of coal at an oblique angle to the direction of the entry, then breaking down and removing a slab along the other entry to a point beyond the line of the end of the slab first broken down along the first entry, breaking down and removing successive slabs each of less length than the preceding slab so that the face of the body of coal left at the conclusion of the second slabbing operation will be oblique to the line of the direction of the entries and will be at an angle opposite to the angle of the face left by the first slabbing operation. 40
- 15 4. The method of mining a body of coal lying between parallel entries which consists of breaking down and removing a relatively long slab along one entry, breaking down and removing successive parallel slabs each of less length than the preceding slab so as to leave the face of the body of coal at an oblique angle to the direction of the entry, portions of the coal in the line of a slab being left standing to serve 45
- 20 as a support for the roof. 50
- 25 5. The method of mining a body of coal lying between parallel entries which consists in breaking down and removing a relatively long slab along one entry, breaking down and removing successive parallel slabs each of less length than the preceding slab so as to leave the face of the body of coal at an oblique angle to the direction of the entry, then breaking down and removing a slab along the other entry to a point beyond the line of the end of the slab first broken down along the first entry, breaking down and removing successive slabs each of less length than the preceding slab so that the face of the body of coal left at the conclusion of the second slabbing operation will be oblique to the line of the direction of the entries and will be at an angle opposite to the angle of the face left by the first slabbing operation. 55
